UNITED STATES PATENT OFFICE.

HERBERT L. BORCHERS, OF LAKWOOD, OHIO, ASSIGNOR TO NATIONAL CARBON CO.
INC., A CORPORATION OF NEW YORK.

MACHINE FOR CRIMPING DRY-CELL JACKETS.

Application filed June 1, 1921. Serial No. 474,221.

To all whom it may concern:

Be it known that I, HERBERT L. BORCHERS, a citizen of the United States, residing at Lakewood, in the county of Cuyahoga and 5 State of Ohio, have invented certain new and useful Improvements in Machines for Crimping Dry-Cell Jackets, of which the following is a specification.

This invention relates to crimping machines and particularly to an improved machine for crimping jackets for dry cells, but it will be understood that various novel features thereof may be employed in other types of machines for operating on tubular 15 articles.

Cells of dry batteries have heretofore generally been enclosed in jackets made of tubular paper or cardboard bodies having separate cupped paper caps glued to and 20 closing the bottom ends thereof. Such jackets are not entirely satisfactory because these caps often loosen and drop off, and the construction is also comparatively expensive and unattractive.

25 A dry cell jacket having an inwardly crimped bottom end is a more reliable, inexpensive and attractive construction, and one of the objects of this invention is to provide a comparatively simple machine in 30 which such jackets may be economically crimped.

Another object of this invention is to provide a novel combined chuck and crimping mechanism especially adapted for crimping the ends of such jackets and similar tubular bodies.

The above and other objects and the novel features of this invention will be apparent from the following description taken in connection with the drawings, in which—

40 Figs. 1 and 2 are, respectively, a side elevation and a top plan view of a crimping machine embodying this invention.

Fig. 3 is a rear view of the same, with the 45 rear frame cover removed, showing parts within in elevation.

Fig. 4 is a vertical sectional view of the same, on the line 4—4 of Fig. 2, parts being shown in elevation,

50 Figs. 5 and 6 are sectional views of the same taken respectively on the lines 5—5 and 6—6 of Fig. 4,

55 Fig. 7 is a view partly in section showing the chuck, crimper and associated mechanism,

Fig. 8 is a detail sectional view of the turret lock, taken on the line 8—8 of Fig. 7.

Fig. 9 is a cross sectional view of a chuck, taken on the line 9—9 of Fig. 7,

Fig. 10 is a view in elevation of a pair 60 of chucks and the ejecting mechanism associated therewith,

Fig. 11 is a detail sectional view, on the line 11—11 of Fig. 10,

Fig. 12 is a plan view of the turret driving mechanism looking down at line 12—12 of Fig. 4,

Fig. 13 is a detail view of mechanism for releasing the spindle latching device,

Fig. 14 is a detail view of the paraffin applying device,

Fig. 15 is a vertical sectional view of a complete dry cell jacket as crimped in the crimping machine of the present invention,

Fig. 16 is a sectional view of the same 75 taken on the line 16—16 of Fig. 15, and

Fig. 17 is a view illustrating a dry cell enclosed in and combined with a crimped jacket embodying the present invention.

Generally speaking, a jacket crimping machine embodying the present invention comprises a suitable carrier, such as the intermittently rotatable turret T, which has a series of tube gripping devices, such as the chucks C, mounted thereon. The turret 80 moves the chucks in succession past means for applying oil to the ends of the tubular bodies, to a station where these bodies are automatically operated upon, and then to a station where the tubular bodies are automatically ejected from the chucks, as by the stripping means E.

In the present machine the means for operating on the tubular bodies comprises a spinning or crimping mechanism, having a fixed crimping member S that is rotatable and movable relatively to the body to be operated upon and cooperates with successive crimping members S' on the chucks to crimp or roll the end of such body 85 inwardly upon itself. The turret is desirably locked during the crimping operation.

The turret, the crimping means and the associated mechanism are operated from suitable power means, such as an electric motor M located in the base B of the machine 90 frame F.

Referring to the drawings, Fig. 4 particularly, the turret T comprises a horizontally disposed table secured to a hub 20 that is rotatable on the support 21 mounted on a 110

pedestal 22 supported on a ledge 22' on the base B. The hub 20 carries a spur gear 20' that meshes with the spur gear 23' on a shaft 23 which may be intermittently rotated, as by a geneva gear G (see Figs. 4 and 12) consisting of the gear member 24 having the usual radial slots 241 engageable by a pin or roller 251 on a gear member 25 keyed to the main drive shaft D, whereby one revolution of the latter turns the turret 90 degrees. The shaft D is continuously rotated during the operation of the machine by the worm gearing W, comprising a worm driven by a pulley F, that is belted to the motor M by the belt M'. Suitable anti-friction bearings may be provided for the rotating parts as shown.

A plurality of chucks C are mounted on the turret T, and as shown these chucks may be arranged in pairs. Each chuck is adapted to internally engage and support a tubular body, such as a tubular paper jacket J and, while the machine is especially suitable for crimping the ends of straight-lapped paper jackets which have an extra thickness of paper at the lap, it will be understood that novel features of the machine may be embodied in machines for operating upon or crimping other tubular articles. By the duplex arrangement illustrated, the production of a given machine is considerably increased without a proportional increase in the cost of the machine or power, which materially reduces the crimping expense per jacket.

Inasmuch as the chucks are alike in construction, only one of them will be described in detail. Referring to Figs. 7 and 9, each chuck comprises a base 26 having a stem 261 that depends through an opening in the turret T, and having an axial opening to provide a sliding bearing for the chuck spindle N. The chuck comprises a number of longitudinally extending gripping sections 27 which may have curved exterior faces which fit into and form a substantially cylindrical supporting surface for the tubular jacket J. The segmental sections 27 have registering transverse grooves 271 near their ends to receive circumferential elastic bands R which are so tensioned as to hold the sections together and tend to contract them inwardly toward the axis of the chuck. The chuck sections 27 are supported at their lower ends on the base 26 and have radially inwardly extending ribs 272 provided with projecting portions 273 adapted to engage under a collar 262 on the base to hold the sections in place on the base. Portions of the ribs 272 fit in slots 281 of a wedge block 28 that is splined on the spindle N to permit the latter to move longitudinally independently of the wedge block and chuck. The bottoms of the slots 281 are inclined as at 282 and cooperate with inclined

portions 274 of the ribs 272, and a spring 29 presses the wedge block 28 against the chuck sections to yieldingly push them outwardly against the tension of the bands R so that the chuck will automatically adjust itself to firmly grip tubes varying slightly in diameter.

Each chuck also has combined therewith a lower spinning or crimping member S' with which the fixed upper spinning or crimping member S is adapted to cooperate as each chuck is moved to the crimping station. The lower crimping member S' is disposed above and movable axially of the chuck and comprises a hardened plate 30 provided with a groove 301 that cooperates with a groove in the upper crimping member S. The grooved plate 30 is clamped between two rings 31 and 32 which may be connected together by screw threads, the inner ring 31 being rotatably supported on the chuck spindle N, as by the anti-friction bearings 311 and held in place on said spindle by a nut 33. The ring 31 also has radial teeth 312 on its upper face adapted to interlock with similar teeth on the upper crimping member S to clutch the two crimping members together so that they will rotate in unison when the upper crimping member S is rotated. The nut 33 also clamps a spring abutment 34 to the spindle N, the ring 32 having an inwardly extending flange 321 that engages beneath the outer edge of the abutment 34 whereby the upward movement of the lower spinning head S' is limited without interfering with its rotation. One end of a helical spring 35 bears against the abutment 34 and the other end thereof abuts against a stationary spring support 36 that rests on the upper ends of the inwardly projecting ribs 272 of the chuck sections. During the operation of the machine, the spindle N is depressed against the tension of the spring 35 as the crimping operation proceeds, carrying the abutment 34 and the crimping head S' downwardly with it as the crimping heads S and S' rotate together and crimp the upper end of the tube into the cooperating grooves of the members S and S'. The compressed spring 35 then serves as a means for restoring the crimping member S' to its initial position when the crimping operation is completed and the spindle N is freed to ascend.

The upper crimping member S which operates with the crimping member S' comprises a hardened crimping ring 38 which has a depending rim 381 flared as at 382 to surround the end of the tube to be crimped. The ring 38 also has a groove 383 that cooperates with the groove 301 in the crimping ring 30 to bend the end of the tube inwardly upon itself and parallel to the axis of the tube as the cooperating rotating

crimping heads descend. The inner edge of the ring 38 is held between two clamping rings 39 and 40, connected by screw threads as shown in Fig. 7. The clamping ring 40 has radial teeth 401 adapted to engage the teeth 312 on the ring 31 to couple the crimping members S and S' together. The clamping ring 39 may be secured by screw threads on the lower end of a spindle L which is journaled in an anti-friction bearing 411, the outer race of which is supported by a ring 41 secured by threads to the lower end of a sleeve 42 slidably in a boss 421 and carried by a lowering and lifting head H.

Inasmuch as the chucks and the associated crimping mechanisms are arranged in pairs, the lifting and lowering device H is arranged so as to lift and lower the two upper crimping heads S simultaneously, and as shown in Figs. 4, 6 and 7 particularly, carries a cam roller 43 that is supported on a shaft 431 journaled in suitable anti-friction bearings 432 on the head H. The cam roller 43 runs in a cam groove 441 in the cam 44 that is secured on the main drive shaft D to rotate therewith, the cam groove 441 being designed so as to lower and lift the head H the desired amount at the proper time for crimping the end of the jacket.

The fixed pair of crimping members S at the crimping station are arranged to be simultaneously rotated by suitable mechanism while the head H reciprocates them. As illustrated, the pair of spindles L project upwardly through parallel sleeves 42 to which the head H is clamped, as best shown in Fig. 6, and the upper ends thereof are splined to spur gears 48, both of which mesh with a single spur gear 49 that is driven by beveled gears 50 and 51 and suitable shafting from a pulley 52 connected by the belt M' to the electric motor M. The cover member 53 may be provided with suitable bearings for parts of this driving mechanism and also carries caps 531 into which the upper ends of the spindles L are movable when the crimping members S are lifted by the head H. Accordingly, the pair of crimping members S are simultaneously rotated at the same rate from a common gear while they are lowered and lifted by a common cam-operated head H.

The pairs of lower crimping members S' descend with the upper pair of fixed crimping members S as the crimping operation proceeds. In order to relieve strain on the crimping mechanism, it is desirable that the pairs of lower crimping members S' be positively depressed. This may be accomplished by a cam 55 mounted on and rotatable with the main drive shaft D. A lower cam face 551 of this cam engages a cam roller 56 carried by a cross bar 57 that is secured by screws 571 to the lower ends of a pair of chuck spindles N. As the cam 55 rotates, the spindles N of the chucks in the crimping position are simultaneously depressed to the same extent as the cam 44 depresses the head H so that the cooperating pairs of crimping members S, S' move together axially of the tubes as the crimping operations proceed. As the crimping operation is completed, the lower cam face 551 of cam 55 further depresses the spindles N until the shoulders 285 of spindles come in contact with and depress wedge blocks 28 against the action of springs 29, thereby permitting the rubber bands R to contract, causing the chuck jaws 27 to collapse. This action releases the crimped jackets, permitting them to be removed by the strippers E.

It is now desirable that the spindles N and the lower crimping members S' at the upper ends thereof be held in depressed position until the crimped jackets are removed from the chucks. Otherwise it would be difficult to remove the jackets, and the lower crimping members S' might pull out the inwardly bent end of the tubular paper body and destroy the results of the crimping operation. For this purpose, a suitable latch K may be pivoted as at 60 on a bracket 601 depending from the lower side of the turret, the latch being provided with a notch 61 at the lower edge thereof adapted to hook over the upper edge of the plate 57 when the latter and the spindles N and the crimping members S' have been depressed the full extent. The latch K is so weighted that the notch 61 will interlock with the plate 57 at the desired time, after which the crimping members S' are held in depressed position with the chucks collapsed until after the crimped jackets have been removed from the chucks and new tubes substituted.

During the crimping operation the turret is desirably locked against rotation to prevent creeping thereof due to the friction between the elements of the geneva gear mechanism G. As illustrated in Figs. 7 and 8, the periphery of the turret is provided at intervals with sockets 64 adapted to receive the locking head 651 at the end of a locking bolt 65 movable in a guide 653 and normally pressed outwardly by a spring 652. The locking bolt 65 is released and retracted at the proper times by a lever 66 pivoted at 661 and provided with a forked end 662 that straddles a pin 654 on the locking bolt 65. The lever 66 carries a cam roller 67 that runs in a cam groove 552 in the upper side of the cam 55, which effects the desired operation of the lever 66 each time that a pair of chucks moves into and out of crimping position.

After two jackets have been crimped at the crimping station, the turret advances the pair of chucks with the jackets thereon to the position where they are to be removed from the chucks. The ejecting or

stripping mechanism E is adapted to simultaneously strip a pair of jackets from a pair of chucks, a stripping cylinder 68 being associated with each chuck. Each stripping cylinder has an outwardly flaring mouth or lip 681 adapted to facilitate the insertion of the tubular body, and an internal ledge 682 upon which the tube is supported during crimping operation. The cylinder 68 extends a short distance up around a portion of the sectional chuck to sustain the lower end of the jacket. The cylinder 68 surrounds and has a sliding fit with the base 26 and rests upon the upper side of the turret T. The cylinders 68 may be lifted by an angular lifting member 70, the lower side 701 of which is adapted to rest on the upper surface of the turret T and is provided with openings 702 to receive the lower ends of the cylinders 68, the latter being provided with flanges 683, forming shoulders projecting over the edges of the openings 702 whereby the cylinders 68 will be lifted when the lifting device 70 rises. The other side 703 of the lifting member 70 is secured to a slider 71 that has suitable openings to receive vertical guide rods 72 mounted on the turret T. The slider 71 also carries a cam roller 711 on its inner side which is adapted to engage a stationary cam 73 which lifts the slider 71 and its associated ejecting cylinders along the guide rods 72 when the turret rotates from the crimping position to the stripping position, as indicated in Figs. 1 and 3.

Accordingly, when the cylinders 68 are lifted, they will carry upward the crimped jackets which rest on the ledges 682 thereof, stripping them from the chucks. By the horizontal portion 731 of the cam 73, the cylinders are held in the raised position during the entire time that the pair of chucks is opposite the stripping position. A bar 80 may also be arranged to pass through the slots 684 in the strippers so as to engage beneath the jackets when they are raised and support them temporarily in this position when the strippers descend by dropping off the end of cam 73, allowing the jackets to fall off into a suitable receptacle. After leaving the stripping position, and while moving another quarter turn, the stripping mechanism is restored to its initial position ready for the insertion of two more tubes onto the pair of chucks. After insertion of two more tubes the pair of chucks are moved another quarter turn, upon leaving this position the latch device is released and the lower crimping members S' are raised to their initial positions by the springs 35. The latch device may be released by suitable means, as by cam segment 622 secured to a guard member 76 and arranged to engage the roller 62 at the outer end of the latch K to swing

it upwardly about the pivot 60 and trip the notch 61 away from the plate 57. Before the roller 62 reaches the segment 622, the roller 56 engages a cam segment 564 carried by the guard 76 to depress the plate 57 so that the notched member 61 may be readily drawn away from the plate 57. The springs 35 and 29 which are under compression, will then act and immediately raise the spindles N and associated crimping members to their normal position, at the same time expanding the chucks to cause them to hold the tubes tightly.

The cam 73 is mounted on a stationary cam cylinder 74 that is secured to the pedestal member 21 and a cover 75 is secured to the upper side of the cam cylinder 74 to enclose the parts and exclude dust therefrom and guard member 76 encloses the mechanism below the turret. A spring supported roller 77 may be provided to automatically take up the slack in the belt M'. The frame F may be provided with a removable rear cover F' to enable the mechanism to be readily inspected and repaired.

The upper ends of the tubular blanks may have a coating of suitable substance such as paraffin oil applied thereto to facilitate the crimping operation and to assist in retaining the crimp. As illustrated in Figs. 2, 3 and 14, the paraffin applying means may consist of a set of three rollers 83, 84 and 85, the former running in a paraffin oil container 86 and wiping against a felt surface on the roller 84 which in turn wipes against the felt surface of roller 85, the latter engaging and coating the upper ends of the tubular bodies as they pass on their way to the crimping mechanism. The rollers may be suitably mounted in an arm 88 that is pivoted at 89 on a bracket 90 secured to the machine frame. A pin or roller 91 on another arm 92 secured to the arm 88, engages a lug 93 to support the frame and the rollers thereon.

A finished jacket J embodying the present invention is illustrated in Figs. 15, 16 and 17 wherein J' illustrates the inwardly crimped end of the tube. As illustrated, the tube that is crimped may be initially formed from a flat paper or cardboard blank one side of which may carry decorating, printing or advertising matter. The blank may be more readily printed in the flat and then may be formed into a cylinder and the edges thereof lapped and cemented or glued together, providing a double-wall seam J'' that is parallel to the axis of the cylinder. The inwardly crimped paraffined end J' forms a stiffened shoulder upon which the dry cell X may be supported, the internal diameter of the jacket J being such that it snugly fits a dry cell about six inches high and two and one-half inches in diameter, in the specific embodiment illustrated. A circular disc Y of pasteboard or

other suitable material is, however, desirably inserted in the jacket J and rests loosely upon the shoulder formed by the inwardly crimped end J' to close the jacket at the bottom and also support the dry cell. The jacket completely encloses the bottom and sides of the cell, leaving the upper end of the cell flush with the jacket and the binding posts X', X'' readily accessible. The cell is raised at least $\frac{1}{8}$ " from the support on which the jacket rests, lost bottom caps are avoided, better insulation is obtained, especially in damp places and the appearance is much improved.

15 While the improved crimping machine and product are shown and described in detail, it is to be understood that various changes may be made therein without departing from the spirit of the invention or sacrificing any of the advantages thereof.

20 I claim:

25 1. In a crimping machine, the combination of a carrier, chucks thereon successively movable thereby to a crimping position, crimping members severally associated with said chucks, a crimping member at said crimping position adapted to successively cooperate with the aforesaid crimping members, and means for moving the cooperating crimping members at the crimping station.

30 2. In a crimping machine, the combination of an intermittently rotatable turret, chucks thereon successively movable thereby to a crimping station, rotatable crimping members severally arranged coaxial with and movable with said chucks, a rotatable and axially movable crimping member at said crimping station adapted to successively cooperate with the aforesaid crimping members, and mechanism for operating the cooperating crimping members at the crimping station.

35 3. In a machine for operating on tubular bodies, the combination of a carrier, pairs of tube chucks thereon successively movable thereby to an operating position, means severally associated with said chucks for operating upon the tubes thereon, a pair of members at said operating position adapted to successively cooperate with the pairs of operating means associated with said chucks, and means for moving the cooperating means at the operating position.

40 4. In a crimping machine, the combination of a carrier, pairs of chucks thereon successively movable thereby to a crimping position, crimping means severally associated with said chucks, a pair of crimping members at said crimping position adapted to successively cooperate with the crimping members associated with said pairs of chucks, and means for simultaneously operating the cooperating pairs of crimping members at the crimping position.

45 5. In a crimping machine, the combina-

tion of an intermittently rotatable turret, chucks thereon successively movable thereby to a crimping station, crimping members severally associated with said chucks, a crimping member at said crimping station 70 adapted to cooperate successively with the aforesaid crimping members, means for releasably locking the turret at the successive crimping station, and means for operating the cooperating crimping members. 75

6. The invention claimed in claim 5 in combination with a shaft carrying cam means adapted to actuate such locking means and such operating means.

7. In a crimping machine, the combination of an intermittently rotatable turret, chucks thereon successively movable thereby to a crimping station, crimping members severally associated with said chucks, a crimping member at said crimping station 80 adapted to cooperate successively with the aforesaid crimping members, means for releasably locking the turret at the successive crimping positions, and means for rotating and reciprocating the crimping member at 90 the crimping station.

8. In a crimping machine, the combination of an intermittently rotatable turret, chucks thereon successively movable thereby to a crimping station, crimping members 95 severally associated with said chucks, a crimping member at said crimping station adapted to cooperate successively with the aforesaid crimping members, means for rotating and reciprocating the cooperating 100 crimping members at the crimping station, and means for removing the crimped articles from the chucks.

9. In a crimping machine, the combination of a turret, chucks thereon successively 105 movable thereby to a crimping position, means for crimping tubes on said chucks, and means for supporting tubes adjacent said chucks during the crimping operation, said means being operative to remove the 110 crimped tubes after such crimping operation.

10. In combination, an intermittently rotatable turret, a pair of chucks thereon movable thereby to an operating position, 115 means for simultaneously operating on articles on said chucks at said operating position, and a pair of devices operative to simultaneously remove the articles from a pair of said chucks after the action of such 120 operating means.

11. In a crimping machine, the combination with a horizontally disposed intermittently rotatable turret, chucks on said turret successively movable thereby to and from a 125 crimping station, crimping means comprising upper and lower crimping members, means for reciprocating the upper crimping member, means for depressing the lower crimping member, means for retaining such 130

lower crimping member in depressed position, a shaft, and cam means on said shaft for operating such reciprocating means and such depressing means.

5 12. In a crimping machine, the combination with a horizontally disposed intermittently rotatable turret, chucks on said turret successively movable thereby to and from a crimping station, crimping means comprising fixed upper crimping mechanism at the crimping station and lower crimping members disposed in and movable with said chucks, means for lowering, raising and rotating said upper crimping mechanism, 10 means whereby said upper crimping mechanism is adapted to be coupled to the lower crimping members when the latter are disposed at the crimping station, means for depressing the lower crimping members, 15 means for temporarily retaining such depressed crimping members in depressed position, and means for removing crimped articles from said chucks.

20 13. In a crimping machine, the combination of a chuck, a crimping member, a spindle carrying said crimping member, a second crimping member, and means for effecting a relative movement between said crimping members and chuck to crimp an article 25 on the latter.

25 14. In a crimping machine, the combination of a hollow chuck, a spindle within said chuck, a crimping member rotatably mounted on said spindle and movable axially thereof within said chuck, a second crimping member cooperating with the aforesaid crimping member, and means for rotating said crimping members in unison to crimp the end of a tube carried by said chuck.

30 15. In a crimping machine, the combination of a chuck comprising a plurality of radially adjustable sections, and cooperating rotatable crimping members adapted to operate on the end of a tube on said chuck and crimp the same inwardly toward the axis of the tube.

35 16. In a crimping machine, the combination with a spindle, of a base, a chuck comprising a plurality of sections abutting against said base and movable radially of said spindle, means for moving said chuck sections outwardly, and a crimping member rotatably mounted on said spindle.

40 17. A chuck comprising a plurality of segmental sections having radially inwardly projecting longitudinal ribs provided with inclined portions, a spindle centrally within said chuck, a wedge block longitudinally movable on said spindle and having inclined 45 means cooperating with said inclined portions of said sections, spring means tending to operate said block to expand said chuck, and means opposing such expansion.

45 18. A combined chuck and crimping de-

vice comprising the combination of a hollow 65 chuck, a spindle extending axially of said chuck, and crimping means rotatably mounted on said spindle adjacent said chuck.

19. The combination with a hollow chuck, of a spindle movable axially of said chuck, 70 a crimping member rotatably mounted on said spindle and movable with said spindle in said chuck, a second rotatable crimping member comprising means whereby the same is adapted to be coupled to the aforesaid 75 crimping member, means for operating said spindle, and means for operating said second crimping member.

20. In a crimping machine, the combination of a chuck, a rotatable crimping member, a spindle carrying said crimping member within said chuck, a second crimping member adapted to cooperate with the aforesaid crimping member, and means for removing a crimped tube from said chuck. 80

21. The combination with a chuck, of a substantially cylindrical member cooperating therewith, said member having a shoulder providing an abutment for one end of a tube during an operation performed on the latter, said member being movable axially of the chuck to strip the tube therefrom. 85

22. In combination, a pair of chucks, and means for simultaneously operating on articles carried by said chucks, comprising a 90 pair of parallel spindles, tools mounted on said spindles, means for simultaneously moving said spindles and the tools thereon axially of said chucks, and means for simultaneously rotating said spindles and the 95 tools thereon while they are being moved.

23. In a crimping machine, the combination with a pair of chucks adapted to fit within tubes, of a pair of rotatable crimping devices for simultaneously crimping tubes on said chucks, and means for simultaneously rotating said pair of crimping devices. 105

24. In a crimping machine, the combination of a pair of chucks, and means for simultaneously crimping articles carried by said chucks comprising axially movable spindles in said chucks, crimping members rotatably mounted on said spindles within said chucks, and a pair of rotatable crimping members adapted to cooperate with the aforesaid crimping members. 110

25. In a crimping machine, the combination of a pair of chucks, crimping devices severally associated with said chucks, means for simultaneously operating said crimping devices, stripping means associated with said chucks, and means for operating said stripping means to simultaneously remove the crimped tubes from said pair of chucks. 120

In testimony whereof, I affix my signature.

HERBERT L. BORCHERS.
